UNITED STATES PATENT OFFICE.

RICHARD GREENLEAF TURNER, OF MALDEN, MASSACHUSETTS.

LOOM.

Application filed May 27, 1919. Serial No. 300,218.

To all whom it may concern:

Be it known that I, RICHARD GREENLEAF TURNER, a citizen of the United States, and a resident of the city of Malden, in the county of Middlesex and Commonwealth of Massachusetts, have invented certain new and useful Improvements in Looms, of which the following is a full, clear, and exact specification.

This invention relates to a type of loom disclosed in my companion application filed June 12, 1917, Ser. No. 174,233, and which eventuated in Patent No. 1,336,545, dated April 13, 1920, wherein a bobbin-carrying shuttle is dispensed with and the weft thread is fed to a point within the shed and thence through an eye formed in the reciprocating shuttle, and thereby woven into the fabric without break for many hours at a time, thus enabling burlap and other woven fabrics to be produced at low cost, whether heavy or light.

In my present loom, I deliver the weft thread into the shed through a hole in the beater frame and hence from below, instead of from above and between the beater and the heddles as in my former construction. Further, I provide two separately moving reeds in place of the comb shown in said application; and disclose a simpler and more efficient means for introducing a locking thread into each selvage.

In the drawings forming part of this specification, Fig. 1 is a diagrammatic side sectional view of a loom embodying my improvements. Fig. 2 is a diagrammatic plan view of the same. Fig. 3 is a sectional detail view of the selvage shuttle and holder. Fig. 4 is a view from beneath of the beater bar showing the reed engaging devices. Fig. 5 is an elevation of the same. Fig. 6 is a detail view of the reed controlling means. Fig. 7 is a sectional detail view of the lock employed in the mechanism. Fig. 8 is a side elevation of the weft-thread tension device. Fig. 9 is an under view of a part thereof.

As shown in Fig. 1, the beater bar 1 is connected by arms 2 to a pivotal support 8 in a well known manner, and the weft thread 3 is fed through a hole 4 in the bar 1, being preferably conducted thereto by a flexible tube 5. Behind the beater bar are two reeds 6, each preferably extending for one-half the width of the shed, but whatever their exact length their inner ends must come in close alignment with the hole 4. These reeds are

independently connected by arms 7 to the pivotal support 8 of the beater frame, and are adapted to be intermittently engaged by and swing with the beater bar 1, in the following manner.

As shown in Figs. 4 and 5, the under surface of the beater bar 1 has pivotally attached thereto four hooks 9, two for each reed 6, one pair facing in one direction and the other pair opposite thereto, a tension spring 10 yieldingly drawing each pair toward the other pair for the engagement thereof with pins 11 (Fig. 1) projecting from the reeds. The two hooks of each pair are tied together to swing simultaneously by a rod 12, and along side of these rods is a bar 13 having lugs 14 engaging pins 15 on the rods, whereby a sliding movement of the bar in one direction, as to the right as illustrated in Fig. 4, will swing the hooks at the right away from the possibility of engaging the associated pins 11, while the spring 10 draws the other pair of hooks into the field of their associated pins, a detent 18 locking the bar.

For thus shifting the bar 13, two levers 16 are pivotally attached to the beater bar 1, and connected at their lower-ends by rods 17 to the pickers 19, the bar 1 having a downwardly and laterally projecting lug 20 designed to be met by first one and then the other of the levers 16 as the pickers 19 are actuated and thereby slide the bar 13 accordingly. Hence each time a picker is actuated, the hooks 9 at its side of the loom are put into condition for engaging the pins 11 of the reed 6 at such side, and when next the beater bar 1 swings back, this reed will be engaged and brought back with it and made to perform the required beater action for that half of the fabric.

In order to yieldingly retain the reeds 6 in their non-beating positions, I attach to arm 7 of each reed a tension spring 21 whose opposite end is attached to a pair of bars 22, 23 between which is slidably carried a bar 24 one end of which is attached to the arm 7. The bar 23 is elongated and coupled with a bar 25 at its other end, between which bars 25 and 23 is slidably located a bar 26 the rear end of which is pivotally anchored, as at 27. A stop 29 prevents the bar 24 from sliding rearward beyond the same, and a pin 30 passing through a slot in the bar 26 similarly controls the latter. This arrangement gives an adjustable resilient support to the reeds,

properly holding them for their engagement by the hooks 9, and as a proper guide for the shuttle.

As shown in Figs. 1 and 2, the shuttle 35 is formed with an elongated eye 36 in a vertical plane, for I find that by having this eye vertical and elongated for nearly the entire length of the shuttle much more perfect work is performed. This shuttle is shot 10 back and forth through the shed on the beater bar 1 by the pickers 19 in a well known manner.

The operation of the loom is as follows: The warp 75 being threaded through the 15 heddles in the usual manner, except that there are four harness frames 76, two frames for each half of the shed. From the heddles the warp passes between the dents composing the reeds 6 to the fabric being woven, 20 and then as the harness frames rise and fall, the shuttle 35 is propelled through the shed from side to side, carrying the weft loop 3 through it. After each cast of the shuttle, 25 one of the reeds 6 is engaged by the hooks 9 and swung forward with the batten 1, properly beating in the last-laid weft thread section; and just before the shuttle 35 leaves a shuttle-box 33, a hook 43 engages the upper weft section and brings it over where 30 it loops around the bobbin or selvage-shuttle 40 thereat. Then as the shuttle 35 speeds toward the other side, this loop slips past the selvage-shuttle until it is stopped by the thread which passes from the selvage- 35 shuttle to the fabric, thus forming a true selvage which will neither unravel or pull out.

What I claim is:

1. A loom comprising a beater frame having a beater bar provided with means for delivering a weft thread through it at a point between its ends, a plurality of harness frames, a shuttle having an eye through which the weft thread passes, and means for

propelling the shuttle along the beater bar. 45

2. A loom comprising a beater frame having a beater bar provided with a channel vertically through it at substantially its mid-length, means for delivering a weft thread up through said channel, a plurality 50 of harness frames, a shuttle having an eye through which the weft thread passes, and means for propelling the shuttle along the beater bar.

3. A loom comprising a beater frame having a beater bar provided with a vertical hole near its mid-length, means including a flexible tube for delivering the weft thread through said hole, a plurality of harness frames, a shuttle having an eye through 60 which the weft thread passes, and means for propelling the shuttle along the beater bar. 55

4. A loom comprising a beater frame having a beater bar, a shuttle having an eye propelled along the beater bar, a plurality 65 of harness frames, means for delivering a weft thread to a point within the shed and thence through said eye to the fabric being woven, a loosely supported bobbin located at each selvage edge of the fabric being woven, a thread from within the bobbin passing to the selvage, and automatically operated means for putting the portion of the weft thread between the fabric and shuttle around said bobbin. 70

5. A loom comprising a beater frame having a beater bar, a shuttle, means for propelling the shuttle along the beater bar, the shuttle having an eye through which is passed the weft thread from a point within 80 the shed to the fabric, and a plurality of harness frames, said eye being extended for nearly the full length of the shuttle. 75

In testimony that I claim the foregoing invention, I have hereunto set my hand this 85 22nd day of May, 1919.

RICHARD GREENLEAF TURNER.
